UNITED STATES PATENT OFFICE.

ORVILLE J. JONES, OF EMMETT, IDAHO.

PUMP-OPERATING ENGINE.

Application filed April 15, 1922. Serial No. 553,042.

To all whom it may concern:

Be it known that I, ORVILLE JEROME JONES, a citizen of the United States, residing at Emmett, in the county of Gem and State of Idaho, have invented certain new and useful Improvements in a Pump-Operating Engine; and I do hereby declare the following to be a full, clear, and exact description of the invention, such as will enable others skilled in the art to which it applies to make and use the same.

This invention is an improved engine which I call a lever weight gravity engine, and which may be operated by weights or springs and is especially adapted for operating a double cylinder pump having reciprocating plungers, but which is also adapted for operating other devices of this kind as well, in which there is a reciprocating element, the object of the invention being to provide an improved engine of this kind which is simple in construction, which may be readily operated, which requires but very little attention, and which when wound will keep a pump in operation for a considerable period of time.

The invention consists in the construction, combination and arrangement of devices hereinafter described and claimed.

30 In the accompanying drawings:—

Figure 1 is a front elevation of a pump operating engine constructed in accordance with my invention, showing the same connected to and arranged for operating a pump,

Figure 2 is a side elevation of the same,

Figure 3 is a vertical sectional view of the same on the plane indicated by the line *a—a* of Figure 2,

40 Figure 4 is a similar view on the plane indicated by the line *b—b* of Figure 2,

Figure 5 is a horizontal sectional view on the plane indicated by the line *c—c* of Figure 1.

45 In accordance with my invention I provide a suitable frame which is here shown as comprising front and rear upwardly converging members 1—2, a plate 3 which connects the upper ends of the members 1, a sill piece or base 4 which connects the lower ends of said members 1, a plate 5 which connects the upper ends of the members 2 and a sill piece or base 6 which connects the lower ends of said members 2. Bearings 7 are secured 55 on the centers of the plates and a rock shaft

8 is mounted in said bearings. A pair of bars 9 connect the members 1—2, near the upper ends of said members, and suitable standards 10 are secured to and supported by said bars 9, said standards having bearings 11 at their upper ends for an axle shaft 12 on which a pair of pulleys 13—14 are mounted for rotation.

The rock shaft is provided with a pendulum rod 15 which depends therefrom near its rear end, a pendulum weight 16 which is here shown as triangular, being secured to the pendulum rod for vertical adjustment said rod passing through a central bore in said pendulum weight and the latter being provided with a set screw 17 which engages said pendulum rod. Tappet pins 18—19 respectively project from the front and rear sides of the pendulum weight 16 at the center thereof and near its lower end.

Shafts 20—21 are mounted in bearings 22 on opposite sides of the frame, and said shafts are each provided with a spur gear and a drum, the spur gear of the shaft 20 being indicated at 23, the drum of said shaft 20 at 24, the sprocket gear of the shaft 21 and the drum thereof at 26. A weight 27 is connected by a suitable cord or cable 28 to the drum 24 and passes over the pulley 14. A similar weight 29 is connected to the drum 26 by a cord 30 which passes over the pulley 13. The drums are fast to the shafts and the spur gears are loose on said shafts and are connected thereto by ratchet wheels 31 and pawls 32 which permit the turning of 90 said shafts, independently of said spur gears in one direction, to cause the cords to be wound upon said drums to raise the weights. Within the scope of my invention any suitable means may be employed for winding 95 up the cords and raising the weights and suitable springs, if preferred, may be substituted for the weights and cords, for revolving the gears 23—25.

Said gears respectively engage pinions 100 33—34 on shafts 35—36, the shafts 35 also having a spur gear 37 and the shaft 36 having a spur gear 38. The gear 37 engages a pinion 39 on a shaft 40 said shaft being also provided with a spur gear 41. The gear 38 105 engages a pinion 42 on a shaft 43, said shaft being also provided with a spur gear 44. The gear 41 engages a pinion 45 on a shaft 46. The gear 44 engages a pinion 47 on the shaft 48. The shafts 35—36—40—43 are 110

- 2
- mounted in bearings on the members 1—2. The shafts 46—48 are mounted in bearings on the cross bars 49 which connect the members 1—2 at the front and rear sides of the frame and are arranged at a suitable distance from the lower ends of said members. The said bars 49 are also provided with bearings for a pair of escapement shafts 50—51 which are respectively provided with escapement wheels 52—53, which are arranged for rotation in reverse directions, and each of which is here shown as provided with five peripheral ratchet teeth 54. The shaft 50 has a pinion 55 which is engaged by a gear 56 on the shaft 46. The shaft 51 has a pinion 57 which is engaged by a gear 58 on the shaft 48. Radial tappet arms 50^a are also secured to the escapement shafts.
- 20 A dog 59 which is pivotally mounted at 60 is held by a spring 61 normally in engagement with the ratchet wheel 52. A similar dog 62 which is pivotally mounted at 63 is held by a spring 64 normally in engagement with the ratchet wheel 53. A lever 65 is provided for releasing the dog 59 from the ratchet wheel 52, is pivotally mounted at 66 and is arranged in the path of the pendulum weight 16. A similar lever 67, which is pivotally mounted at 68, is adapted to trip the dog 62 from the ratchet wheel 53 and is arranged in the path of the pendulum weight.

Hence when the pendulum is swung, and the engine is in operation, the pendulum at the end of its stroke engages one of the levers so that said lever moves one of the dogs against the tension of the spring connected to said dog out of engagement with one of the escapement wheels, and hence said escapement wheel turns through a partial rotation, and one of the tappet arms 50^a engaging one of said tappet pins of the pendulum and imparting a return stroke thereto and hence the pendulum is kept in operation.

A pump 69 is here shown arranged on the front side of the frame and provided with a pair of vertical cylinders 70—71 in which plungers 72—73 respectively operate, said plungers being connected by rods 74—75 to a walking beam 76 which is secured to the front end of the shaft 8. Hence the pump is operated by the engine.

Having thus described the invention, what I claim is:

1. A motor of the type indicated having an operating member consisting of a rock shaft and a pendulum depending therefrom for oscillatory movement, power driven escapement devices having trip members arranged in the path of movement in opposite directions of the pendulum for release of the rotary escapement member at the limit of each stroke of the pendulum and oppositely rotatable power driven star wheels

controlled respectively by the rotary members of the escapement devices and having tappet arms for arrangement successively in the paths of movement of tappet pins carried by the pendulum for alternately imparting impulses in opposite directions to the latter.

2. A motor of the type indicated having an operated member consisting of a rock shaft and a pendulum depending therefrom for oscillatory movement, power driven escapement devices having trip members arranged in the path of movement in opposite directions of the pendulum for release of the rotary escapement member at the limit of each stroke of the pendulum and oppositely rotatable power driven star wheels controlled respectively by the rotary members of the escapement devices and having tappet arms for arrangement successively in the paths of movement of tappet pins carried by the pendulum for alternately imparting impulses in opposite directions to the latter, the star wheels being carried respectively by the rotary members of the escapement devices.

3. A motor of the type indicated having an operated member consisting of a rock shaft and a pendulum depending therefrom for oscillatory movement, power driven escapement devices having trip members arranged in the path of movement in opposite directions of the pendulum for release of the rotary escapement member at the limit of each stroke of the pendulum and oppositely rotatable power driven star wheels controlled respectively by the rotary members of the escapement devices and having tappet arms for arrangement successively in the paths of movement of tappet pins carried by the pendulum for alternately imparting impulses in opposite directions to the latter, the spring actuated verges of the escapement devices being actuatable by trip levers having their terminals disposed respectively in the paths of movement in opposite directions of the pendulum.

4. In combination with a pair of motor mechanisms each including a ratchet escapement wheel, dogs to engage said ratchet wheels, springs to normally hold the dogs in engaged position, levers to trip said dogs, a swinging pendulum to alternately engage said levers and cause them to alternately release the dogs, tappet elements actuated by the escapement wheels to swing the pendulum.

5. In combination with a pair of motor mechanisms each including a ratchet escapement wheel, dogs to engage said ratchet wheels, springs to normally hold the dogs in engaged position, levers to trip said dogs, a swinging pendulum to alternately engage said levers and cause them to alternately release the dogs, and means to

- swing the pendulum upon the release of the dogs, a rocking element actuated by said pendulum and a pump plunger connected to and actuated by said rocking element.
- 5 6. In combination with a pair of motor mechanisms each including a ratchet escape-
ment wheel, dogs to engage said ratchet wheels, springs to normally hold the dogs in engaged position, levers to trip said
- 10 dogs, a swinging pendulum to alternately engage said levers and cause them to alternately release the dogs, and means actuated by the escapement wheels to swing the pendulum, a rock shaft actuated by said
- 15 pendulum, a walking beam attached to said rock shaft and a pump having a pair of cylinders and plungers in said cylinders and respectively arranged to be operated by said walking beam.
- 20 7. The combination with a pair of motor mechanisms each including a ratchet escape-
ment wheel, dogs to engage said ratchet wheels, springs to normally hold the dogs in engaged position, levers to trip said dogs,
- 25 and a swinging pendulum element to alternately engage said levers and cause them to alternately release the dogs, and pendulum actuating means revoluble with the escape-
ment wheels, of motor mechanisms comprising
- 30 ing a drum, a cord attached to said drum for winding thereon, a weight suspended from the cord, and gears connecting the drums to the shaft of said ratchet escape-
ment wheel.
8. In combination, a pair of motor mech-
anisms, each including an escapement, star
wheels operated by said escapements, a pen-
dulum to alternately release said escape-
ments, and tappet elements carried by the
pendulum and actuated by the star wheels to swing the pendulum.
9. In combination, a pair of motor mech-
anisms, each including an escapement, star
wheels rotated by said escapements, a pen-
dulum to alternately release said escape-
ments and means carried by said pendulum
and actuated by the star wheels to swing the
pendulum.
10. In combination, a pair of motor
mechanisms, each including an escapement,
means to engage said escapements, levers to
release said escapement engaging means, a
pendulum to alternately engage said levers
to release the escapements, star wheels ro-
tated by the escapements and tappet ele-
ments actuated by the star wheels to swing
the pendulum.

In testimony whereof I affix my signature in presence of two witnesses.

ORVILLE J. JONES.
